(57) CLAIM

I claim the ornamental design for a fishing lure, as shown and described.

DESCRIPTION

FIG. 1 is a front, right perspective view of a fishing lure.

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines depict environment and are included for the purpose of illustrating only and form no part of the claimed design.
